United States Patent Office

Des. 195,539
Patented June 25, 1963

195,539

SPRAY NOZZLE

Joel K. Williams, 8280 Garden Grove Blvd.,
Garden Grove, Calif.

Filed Dec. 13, 1961, Ser. No. 67,902

Term of patent 3½ years

(Cl. D91—1)

FIGURE 1 is a front perspective view of a spray nozzle embodying my new design;

FIGURE 2 is a front elevational view thereof;

FIGURE 3 is a side elevational view thereof;

FIGURE 4 is a top plan view thereof; and

FIGURE 5 is a rear elevational view thereof.

The hose fragmentarily shown is for illustrative purposes only.

I claim:

The ornamental design for a spray nozzle, substantially as shown and described.
